Primary Examiner — Garth Rademaker(74) Attorney, Agent, or Firm — Woodard Emhardt & Moriarty McNett & Henry LLP(57) CLAIM

The ornamental design for an ellipse vase, as shown and described.

DESCRIPTION

FIG. 1 is a front perspective view of an ellipse vase incorporating my new design;

FIG. 2 is a front elevation view thereof, the rear elevation view being identical thereto;

FIG. 3 is a right side elevation view thereof;

FIG. 4 is a left side elevation view thereof;

FIG. 5 is an enlarged bottom plan view thereof;

FIG. 6 is an enlarged top plan view thereof;

FIG. 7 is a cross-sectional view thereof, taken on line 7-7 of FIG. 2 and shown at an enlarged scale;

FIG. 8 is a partial cross-sectional view thereof, taken along line 8-8 of FIG. 6; and,

FIG. 9 is a partial cross-sectional view thereof, taken along line 9-9 of FIG. 6.
